CLAIM

The ornamental design for a delivery box, as shown and described.

DESCRIPTION

FIG. 1 is a first perspective view of a delivery box, showing our new design;

FIG. 2 is a second perspective view thereof;

FIG. 3 is a third perspective view thereof;

FIG. 4 is a first side view thereof;

FIG. 5 is a second side view thereof;

FIG. 6 is a front view thereof;

FIG. 7 is a rear view thereof; and,

FIG. 8 is a top view thereof.

The broken lines in the figures illustrate the portions of the delivery box and form no part of the claimed design.
